UNITED STATES PATENT OFFICE.

BERTUS A. LAKE, OF BIG PRAIRIE, OHIO.

SADIRON.

Application filed November 2, 1927. Serial No. 230,513.

The invention relates to sad irons and more particularly to a match generator by means of which gas may be generated for lighting the iron with the use of one or more lighted 5 matches placed in the hollow interior of the iron.

The object of the improvement is to provide a gasoline heated sad iron having a generator for generating gas from the gasoline, 10 and arranged to be heated by placing a lit match or the like within the iron adjacent to the generator, a pilot light being preferably located adjacent to the generator and adapted to be lit to continue the generation of gas after 15 the iron is put into operation.

The above and other objects may be attained by providing a sad iron having a hollow body, preferably cast within which is located a burner, a generator tube extending 20 from the fuel tank into the burner and a pilot or generating burner being provided for heating said generator during operation of the iron.

A heating and deflecting plate is attached 25 to the generator tube and extends down into the hollow body of the iron, at an angle to said tube, and in such position that when a lit match or the like is placed in the bottom of the iron, beneath said plate, substantially all 30 of the heat from the flame thereof will be directed and conducted to the generator tube, an opening or slot being preferably provided at the upper end of the plate, at the point where the same connects to the generator tube, 35 whereby the flame is carried upward along the under side of the plate and into contact with the tube.

An embodiment of the invention is illustrated in the accompanying drawing, in 40 which

Figure 1 is a longitudinal sectional view through the improved sad iron, and

Fig. 2, a transverse sectional view through the same, taken substantially on the line 2—2, 45 Fig. 1.

Similar numerals refer to similar parts throughout the drawing.

The iron may comprise the cast iron body portion including the bottom 1 and side walls 2, which latter may be notched or cut away at intervals, in their upper edges, as shown 50 at 3, for the purpose of furnishing sufficient air for combustion.

The top, or cover, of the iron may comprise

the transversely curved casting 4 to which 55 may be attached the handle 5, formed of a metal strap connected to the top casting as by screws 6, and carrying the hand grip 7 of wood or the like.

The fuel tank 8 may be supported as by the 60 bar 9 which may be attached to the cover 4, as by one of the screws 6, the slotted end 10 of said bar receiving the pipe 11 at the lower end of the fuel tank, a nut 12 being provided for detachably securing the tank upon said 65 bar.

The burner 13 may be of the usual construction having the short upper leg 14 and the longer slotted or perforate lower leg 15, connected as by the curved portion 16. 70

This upper leg 14 may be inserted into a hollow boss 17 depending from the cover 4 and detachably secured therein as by the set screw 18.

The generator tube 19 leads from the tank 75 to the burner, and the flow of fuel may be controlled by the usual needle valve shown generally at 20. The usual pilot or generating burner 21 may be provided upon the upper side of the lower leg 15 of the burner in a position to heat the generator tube at a point 80 near its connection to the burner.

The invention pertains to the heating and deflecting plate 23 which may be of sheet metal or the like directly connected at its 85 upper end to the generator tube as indicated at 24, by brazing or the like.

This plate depends downward into the hollow interior of the iron at an angle as illustrated in Fig. 2, and it should be noted that a 90 slot 25 is provided between the upper end of the plate and the generator tube.

In operating the iron, when it is desired to light the same, one or two lighted matches are 95 placed beneath the heating and deflecting plate 23, in such position that the flame therefrom will strike the plate.

The flame will pass upward along the under side of the plate and through the slot or 100 opening 25, thus contacting directly with the generator tube, while at the same time the plate being quickly heated by the flame will conduct heat through the points 24 to the generator tube. 105

When the flame has almost died out the generator tube will be substantially heated to generate gas from the gasoline and the nee-

idle valve may be opened permitting this gas to pass into the burner which will be ignited from the flame of the match.

The pilot or generating burner 21 will also be lighted at the same time, thus continuing the generation of the gas which will in turn be burned in the perforate lower leg 15 of the burner in the usual manner.

From the above it will be obvious that a fuel heated sad iron is provided in which gas may be quickly and easily generated from the liquid fuel to start the operation of the iron and in which the generation of the gas will continue after the burner has been lighted.

15 I claim:

1. A fuel heated iron including a hollow body, a burner in said body, a generator tube leading from a liquid fuel supply to the burner, and a heating and deflecting plate upon the generator tube and within said hollow body, whereby the generator tube will be heated by producing a flame beneath said plate.

2. A fuel heated iron including a hollow body, a burner in said body, a generator tube leading from a liquid fuel supply to the burner, and a heating and deflecting plate connected at one end upon the generator tube and within said hollow body, whereby the generator tube will be heated by producing a flame beneath said plate.

3. A fuel heated iron including a hollow body, a burner in said body, a generator tube leading from a liquid fuel supply to the burner, and a downwardly and angularly disposed heating and deflecting plate upon the genera-

tor tube and within said hollow body, whereby the generator tube will be heated by producing a flame beneath said plate.

4. A fuel heated iron including a hollow body, a burner in said body, a generator tube leading from a liquid fuel supply to the burner, and a downwardly and angularly disposed heating and deflecting plate upon the generator tube and within said hollow body, there being an opening between the plate and generator tube, whereby the generator tube will be heated by producing a flame beneath said plate.

5. A fuel heated iron including a hollow body, a burner in said body, a generator tube leading from a liquid fuel supply to the burner, and a heating and deflecting plate connected at its upper end to the generator tube and depending downward at an angle within said hollow body, whereby the generator tube will be heated by producing a flame beneath said plate.

6. A fuel heated iron including a hollow body, a burner in said body, a generator tube leading from a liquid fuel supply to the burner, and a heating and deflecting plate connected at its upper end to the generator tube and depending downward at an angle within said hollow body, there being an opening between the plate and generator tube, whereby the generator tube will be heated by producing a flame beneath said plate.

In testimony that I claim the above, I have hereunto subscribed my name.

BERTUS A. LAKE.
